UNITED STATES PATENT OFFICE

2,665,048

HEAVY-DUTY FIBER CONTAINER

Samuel P. Belsinger, Atlanta, Ga., assignor to
Belsinger, Inc., Atlanta, Ga., a corporation of
Georgia

Application March 23, 1950, Serial No. 151,480

1 The invention relates to new and useful improvements in a foldable fiber container which is especially adapted for crating eggs, fruits and the like for commercial handling.

An object of the invention is to provide a fiber container by slitting and scoring flat fiber blanks, wherein the container when assembled includes an inner body, a liner for the bottom and end walls of said body, outer protecting walls for said body and partitions for dividing the body into cells of substantially equal capacity.

A further object of the invention is to provide a container of the above type wherein the outer protecting walls include end walls, half front and rear side walls formed integral therewith and a partition member formed integral with each rear side wall and wherein the front side walls and the partitions have holding tabs for rigidly securing the container parts in assembled position.

In the drawings, which show by way of illustration one embodiment of the invention:

Figure 1 is a view showing the four blanks from which the container is formed, each blank being shaped, slit and scored ready for folding and assembling;

Figure 2 is a perspective view of the inner body portion with the front wall and end member carried thereby partly folded toward assembled position;

Figure 3 is a view showing the completed inner body portion and the liner shaped and ready for assembling in the body portion;

Figure 4 is a view showing the inner body portion and liner assembled and the outer protecting walls and partitions in place except for the front half sections which are shown in partly assembled position;

Figure 5 is a view in plan of the assembled container with parts broken away to show the interlocking of the partitions and outer side walls;

Figure 6 is a sectional view on the line 6—6;

Figure 7 is a section of the upper portion of the box taken on the line 7—7 with the cover in closed position;

The invention has to do with a fiber container which is made from a plurality of fiber blanks. One of the blanks is shaped, slit and scored so that they may be folded to form when assembled an inner body portion for the container which includes a bottom wall, front and rear side walls, and cover and end members for partially closing the end of the inner body. A liner for the bottom and end walls is made from a separate fiber blank by shaping and scoring so that when

2 the liner is in assembled position, it fully covers the inner face of the bottom and forms end members constituting inner end walls for the container. Protecting walls for the inner container body are formed from two blanks similar in shape. These blanks are shaped and scored so that when in assembled position the blanks form outer end walls for the container, outer front and rear side walls and also partition walls which divide the container into cells of substantially equal capacity.

Referring more in detail to the drawings the four blanks are indicated in Figure 1. The blank A forms when assembled the inner body portion, blank B forms the liners and the blanks C—C form the outer protecting walls for the inner body.

The inner body blank is slit and scored so as to provide a bottom 1, a rear side 2, a cover 3 formed integral with the rear side, a cover flap 4 and a front side wall 5. The bottom member is also provided with extensions 6—6, which when folded form end members for the inner body. The rear side wall is provided with extensions 7—7 which likewise form end members for the inner body. The front side wall 5 has extensions 8—8 and these extensions when folded and assembled form a portion of the end walls for the inner body.

In Figure 2, this inner blank A is shown as folded along the score lines indicated in the drawings to form a bottom 1 and the rear wall 2. The rear wall carries the cover 3 which is in open position. The front wall 5 is only moved part way toward assembled position for the sake of clearness.

The rear wall is provided with a slot 9 which extends from the bottom of the wall to the top thereof. The front wall is provided with a slot 10 which extends from the bottom part way toward the top, terminating so as to provide the wall with a continuous connecting section 11.

In Figure 3, this inner body is shown in full assembled position. The liner B is scored so as to provide a bottom wall 12 and end walls 13—13. The liner in Figure 3 is shown as placed over the inner body ready for lowering into the body to assembled position.

In Figure 4, this liner is in assembled position and it will be noted that the bottom wall 12 serves as a liner for the bottom of the inner body and it extends from end to end and side to side of said body. The end members of the liner 13—13 when in assembled position extend from top to

bottom and side to side forming inner end walls for the inner body.

The blanks C—C are as noted similar in shape and the description of one will answer for the other. Each blank has an end member 14 extending the full height and width of the outer end face of the container. Formed integral with this end member 14 is a half rear wall section 15 and formed integral with the rear half wall section 15 is a partition wall 16 provided with a flap 17. Also provided integral with the end member 14 is a front half side wall 18 and the front half side wall has a flap 19 formed integral therewith which extends only part way of the height of the side wall. The same is true of the flap 17. They only extend part way of the height of the wall 16.

In this Figure 4, these blanks are shown as in assembled position on the inner body of the container. The end members 14 form outer end walls for the body. The partition members 16—16 are passed through the slot 9 and the tabs 17—17 are passed through the slot 10 in the front wall. These tabs are folded back against the outer face of the front wall of the inner body. The members 15—15 lie close against the rear wall and form an outer rear wall section. The tabs 19 on the front wall half sections 18 are passed through the slot 10 and between the partition members. These front half side walls when in position form a front outer wall and the tabs 17—17 lie between the inner and outer sections of the front wall of the container. The tabs 19—19 lie between the partition members 16—16 as clearly shown in Figure 5. The tab 4 on the cover 3, when in closed position, lies between the front inner body wall section 5 and the outer half body wall sections 18—18 and will be frictionally gripped between said sections. The tabs 19—19 will be frictionally gripped between the side walls and if desired, a holding staple may be passed through the partitions and the tabs as indicated at 20.

The end members of the liner 13 may, if desired, be provided with extensions to form inner cover sections or one of the end members may be provided with a cover section extending the full length of the container. It is noted that the container when in final assembled position has a double bottom wall, double end walls and double side walls and these parts are all rigidly held in assembled position by the locking tabs. The container blanks may be shipped in flat condition to place of use and the container quickly assembled. No stapling of the container is necessary and, therefore, the container, after it has performed its purpose, may be readily disassembled into the flat blank condition and these flat blanks returned to the packer for reuse.

There are certain kinds of truck shipments 60 which do not require double bottom and ends and, therefore, in containers for such use the liner 12 and inner end walls 13—13 will be omitted. When

these are omitted, the box still will be complete and strong and durable for shipment purposes.

It is obvious that minor changes in the details of construction may be made without departing from the spirit of the invention as set forth in the appended claims.

I claim:

1. A foldable fiber container formed from blanks shaped, slit and scored so as to provide when assembled a container comprising a bottom having partial end portions formed integral therewith, front and rear side walls formed integral with the bottom wall, partial end walls formed integral with the front and rear side walls, each side wall having a transverse slit intermediate the ends thereof, a cover formed integrally with said rear wall, and separate blanks providing outer end walls engaging and covering the partial end walls on the bottom and side walls, each outer end wall having a half rear side wall, a partition wall and a flap, said partition walls extending through the slot in the rear wall and said flaps extending through the slot in the front wall and folded back against the outer front wall, each outer end wall having a half front side wall and a flap which extends through the slot in the front wall and between the partition walls.

2. A foldable fiber container formed from blanks shaped, slit and scored so as to provide when assembled a container comprising a bottom having partial end portions formed integral therewith, front and rear side walls formed integral with the bottom wall, partial end walls formed integral with the front and rear side walls, each side wall having a transverse slit intermediate the ends thereof, a cover formed integrally with said rear wall, and separate blanks providing outer end walls engaging and covering the partial end walls on the bottom and side walls, each outer end wall having a half rear side wall, a partition wall and a flap, said partition walls extending through the slot in the rear wall and said flaps extending through the slot in the front wall and between the partition walls.

3. A foldable fiber container formed from blanks shaped, slit and scored so as to provide when assembled a container comprising a bottom having partial end portions formed integral therewith, front and rear side walls formed integral with the bottom wall, partial end walls formed integral with the front and rear side walls, each side wall having a transverse slit intermediate the ends thereof, a cover formed integrally with said rear wall, and separate blanks providing outer end walls engaging and covering the partial end walls on the bottom and side walls, each outer end wall having a half rear side wall, a partition wall and a flap, said partition walls extending through the slot in the rear wall and said flaps extending through the slot in the front wall and folded back against the outer front wall, each outer end wall having a half front side wall and a flap which extends through the slot in the front wall and between the partition walls.

4. A foldable fiber container formed from blanks shaped, slit and scored so as to provide when assembled a container comprising a bottom having partial end portions formed integral therewith, front and rear side walls formed integral with the bottom wall, partial end walls formed integral with the front and rear side walls, each side wall having a transverse slit intermediate the ends thereof, a cover formed integrally with said rear wall, and separate blanks providing outer end walls engaging and covering the partial end walls on the bottom and side walls, each outer end wall having a half rear side wall, a partition wall and a flap, said partition walls extending through the slot in the rear wall and said flaps extending through the slot in the front wall and folded back against the outer front wall, each outer end wall having a half front side wall and a flap which extends through the slot in the front wall and between the partition walls, and a separate liner for said bottom wall having formed integral therewith inner end walls engaging the inner faces of the partial end walls carried by the bottom wall and side walls.

SAMUEL F. BELSINGER.
